US0D1075747S

(12) **United States Design Patent** (10) **Patent No.:** **US D1,075,747 S**
(45) **Date of Patent:** **** May 20, 2025**

(54) **LAPTOP**

(71) Applicant: **Super Laptop Computer Limited**,
Hong Kong (HK)

(72) Inventor: **Ensheng Zhang**, Zhanjiang (CN)

(73) Assignee: **Super Laptop Computer Limited**,
Hong Kong (HK)

(**) Term: **15 Years**

(21) Appl. No.: **29/916,939**

(22) Filed: **Nov. 16, 2023**

(51) LOC (15) Cl. **14-02**

(52) U.S. Cl.

USPC **D14/315**

(58) **Field of Classification Search**

USPC D14/315-318, 320, 327, 341, 345, 346,
D14/439, 440, 444, 388, 389, 432
CPC G06F 1/1613; G06F 1/1616; G06F 1/1656;
G06F 1/1681; H05K 5/0017; H05K
5/0018; H05K 5/0213

(57) **CLAIM**

The ornamental design for a laptop as shown and described.

DESCRIPTION

FIG. 1 is a front, right and top perspective view of a laptop, showing my new design;

FIG. 2 is a rear, left and top perspective view thereof;

FIG. 3 is a rear, left and bottom perspective view thereof;

FIG. 4 is a front view thereof;

FIG. 5 is a rear view thereof;

FIG. 6 is a left side elevation view thereof;

FIG. 7 is a right side elevation view thereof;

FIG. 8 is a top plan view thereof;

FIG. 9 is a bottom plan view thereof;

FIG. 10 is an enlarged view of an encircled area labeled “10”

in FIG. 1;

FIG. 11 is an enlarged view of an encircled area labeled “11”

in FIG. 1;

FIG. 12 is an enlarged view of an encircled area labeled “12”

in FIG. 1;

FIG. 13 is an enlarged view of an encircled area labeled “13”

in FIG. 2; and,

FIG. 14 is an enlarged view of an encircled area labeled “14”

in FIG. 2.

The broken lines depict portions of the laptop that form no

part of the claimed design.

The dot-dash broken lines in FIGS. 1, 2, 10, 11, 12, 13, and

14, framing portions of the claimed design that are illus-

trated from enlargements form no part of the claimed design.

1 Claim, 14 Drawing Sheets
